United States Patent Office

Des. 187,984
Patented May 24, 1960

187,984

CHAIR

Abraham I. Zwickel, Brooklyn, N.Y., assignor to Nu-Lite Products, Inc., a corporation of New York

Filed Sept. 4, 1959, Ser. No. 57,449

Term of patent 14 years

(Cl. D15—1)

FIG. 1

FIG. 2

FIG. 4

FIG. 3

Figure 1 is a perspective view of a chair, showing my new design;

Figure 2 is a plan view thereof;

Figure 3 is a side elevational view thereof; and

Figure 4 is a sectional view taken along line 4—4 of Figure 3.

The features of my design are shown in full lines and consists of tubular arms bent and flattened substantially as shown.

I claim:

The ornamental design for a chair, substantially as shown and described.
